(57) **CLAIM**

The ornamental design for a golf ball corn cob holder, as shown and described.

DESCRIPTION

FIG. 1 is a top isometric view of a golf ball corn cob holder showing the golf ball handle and tee shaped prong arrangement of my new cob holder design;

FIG. 2 is a top view thereof, the bottom view being a mirror image thereof;

FIG. 3 is a right side view thereof, the left side view being a mirror image thereof;

FIG. 4 is a back view thereof; and,

FIG. 5 is a front view thereof.
